UNITED STATES PATENT OFFICE

TOM HUSTON, OF COLUMBUS, GEORGIA

DESIGN FOR A DISPLAY CONTAINER FOR FOODS, CONFECTIONS, AND THE LIKE

Application filed January 14, 1929. Serial No. 29,592. Term of patent 14 years.

To all whom it may concern:

Be it known that I, Tom Huston, a citizen of the United States, residing at Columbus, in the county of Muscogee and State of Georgia, have invented a new, original, and ornamental Design for Display Container for Foods, Confections, and the like, of which the following is a specification, reference being had to the accompanying drawing, forming a part thereof.

The single figure of the drawing is a perspective view of a container embodying my new design.

I claim:

The ornamental design for a display container for foods, confections and the like, substantially as shown.

In testimony whereof, I, Tom Huston, affix my signature.

TOM HUSTON.
